UNITED STATES PATENT OFFICE.

WILLIAM P. DENTON, OF SOUTH MELBOURNE, VICTORIA, AUSTRALIA, ASSIGNOR OF ONE-THIRD TO GEORGE WALTER LONG AND ONE-THIRD TO GEORGE OLIVER LONG, OF SOUTH MELBOURNE, AUSTRALIA.

AIR-BLOWER.

1,333,294.

Specification of Letters Patent.

Patented Mar. 9, 1920.

Application filed July 7, 1919. Serial No. 309,057.

To all whom it may concern:

Be it known that I, WILLIAM PATCHETT DENTON, residing at South Melbourne, in the State of Victoria, Commonwealth of Australia, a subject of the King of Great Britain, have invented certain new and useful Improvements in and Connected with Air-Blowers, of which the following is a specification.

10 This invention has reference to the construction of air blowers of the centrifugal type used for ventilating, forge work and other purposes where the movement of large volumes of air is required.

15 In constructions hitherto employed, rotor blades have been made in such a way that the pressure of air upon the whole width of the blade has not been approximately uniform, with the consequent result that eddying is set up in the discharge and the velocity of same is impaired.

20 I propose, in this invention, to attempt to remedy these defects, and by a special construction of rotor blade to insure that a more even pressure of air will be maintained upon the whole length of blade of the driven rotor. Accordingly, I construct rotor blades with a middle part about the same width as at present obtains in this class of machinery 25 but with the width expanding slightly toward each end of the blade, the expansion toward the front or air intake end being slightly greater than toward the other end.

30 Further details of construction are herein-after referred to and with reference to the accompanying drawings, in which,

Figure 1 is a perspective view of a blower fitted with the improvements.

Fig. 2 is a like view of a single blade.

40 Fig. 3 shows in front elevation several blades fitted into their supports, and

Fig. 4 is a like view of part of the ring supporting the blade ends.

45 The rotor is housed within a snail conduit in the casing 5 in which is an air intake opening and a discharge orifice 6. The latter should be the whole width of the casing and slightly higher than it is wide.

50 The blades 7 are more or less curved in the ordinary way and are provided at each end with right-angularly disposed lugs 8 by which the same are secured to supports in the rotor. At the air intake side the support may consist of a ring 9 and at the

other or rear side, of a plate or another ring 55 to which the lugs on the blades are riveted.

Arms 10 are between the boss of the rotor and the blades and connected to the latter at their middle part, as shown. From the middle or narrowest part of the blade the 60 upper edge inclines upward toward each end. The blade is broadest at its front or air intake end and is extended below the flange 8 and curved as shown, the radius of the curve being as great as possible. The 65 opposite end of the blade is nearly as wide as the front end, but not quite, and its lower edge inclines downwardly from the rear toward the front or curved part at a slight acute angle to the horizontal. 70

By means of this construction the indrawn air is gripped immediately by the somewhat broader end of the blade while the rest of the blade takes on its proper share, thus insuring a full delivery through the discharge. 75 The roof of the latter is inclined upwardly from the horizontal at an angle of about 30 degrees and the position of the rotor within its casing relatively to the discharge opening is such that the said inclined roof to the 80 discharge inclines directly toward the rotor axis. Thus, as the rotor is driven the blades will create an approximately equal suction along the full length of same and provide for a steady discharge of the air through the 85 delivery in the blower casing.

Having now described my invention what I claim as new and desire to secure by Letters Patent is:

1. In an air blower, a rotor, blades in the 90 rotor that are narrowest at the middle part and expand in width toward each end, the end adjacent to the air intake being widest and means for supporting the blades in the rotor. 95

2. In an air blower, a rotor, blades in the rotor that are narrowest at the middle part and expand in width toward each end the front end being widest and the lower edge of each blade inclining downwardly from 100 the rear to the front and means for supporting the blades in the rotor and for driving the same.

3. In an air blower, blades to the rotor that are narrowest at the middle part and expand in width toward each end with a greater width at the front end, rightangularly disposed lugs on each blade end, a ring

2
to which the lugs are attached into the rotor, means for supporting the blades in the rotor and means for taking air into and for discharging it from the blower.

- 5 4. In an air blower, blades to the rotor that are narrowest at the middle part and expand in width toward each end and that on the lower edge incline downwardly from the rear to the front ends, means for supporting the blades in the rotor, a casing thereto, an air intake therein adjacent to 20 the wider ends of the blades and a discharge therefrom, that is as wide as the casing but higher than it is wide and having a roof inclining upwardly toward the rotor axis.
- 10 5. In an air blower, blades to the rotor supporting the blades in the rotor, a casing thereto, an air intake therein and a discharge therefrom the roof of the discharge inclining upwardly toward the rotor axis.

that are narrowest at the middle part and 15 expand in width toward each end and that on the lower edge incline downwardly from the rear to the front ends, means for supporting the blades in the rotor, a casing thereto, an air intake therein adjacent to 20 the wider ends of the blades and a discharge therefrom, that is as wide as the casing but higher than it is wide and having a roof inclining upwardly toward the rotor axis.

In witness whereof I affix my signature. 25
WILLIAM P. DENTON.
